MEANS FOR APPLYING MATCH IGNITION MATERIAL TO BOOK MATCHES, ETC.

Charles F. Wright, Akron, Ohio, assignor to The Diamond Match Company, New York, N. Y., a corporation of Delaware

Application November 29, 1938, Serial No. 242,941

10 Claims. (Cl. 91—50)

This invention relates to means for applying ignition material to match book covers and the like; having reference more especially to mechanism for use in connection with a match book-
5 ing machine of the type disclosed in Letters Patent of the United States No. 1,042,472 dated October 29, 1912.

In machines of the type referred to a succession of match books, each comprising match cards 10 with a cover folded at one end and fastened to the bases of the cards, are held in the links of an endless carrier and thereby transported in close relation to the periphery of a wheel by means of which a quantity of ignition "paint" is applied 15 to the external surface of the fastened cover fold. Owing to the unevenness of the surfaces of the fastened cover folds the ignition material applied thereto frequently presents irregular longitudinal edges which detract from the 20 appearance of the product.

The object of my invention is to provide simple and efficient means whereby the ignition material is applied to the cover in a manner to present a smooth match striking surface having 25 uniform longitudinal edges, as will be herein-after described and claimed.

In the annexed drawings—

Figure 1 is a plan of ignition paint applying mechanism embodying a form of my invention, 30 showing a portion of the match book carrier.

Fig. 2 is a front elevation of said mechanism.

Fig. 3 is a transverse vertical section, as on the line 3—3 of Fig. 2.

Fig. 4 is a partial longitudinal vertical section, 35 as on the line 4—4 of Fig. 3.

Fig. 5 is a view showing a portion of the grooved paint-applying wheel and its associated flanged hold-down wheel, the latter bearing upon the folded end of an interposed book of matches and 40 being partly in section.

Fig. 6 is a similar view showing the succeeding paint-applying wheel and its associated hold-down wheel.

Fig. 7 is a view of a portion of a match book 45 with parallel stripes of ignition material on its end fold.

Fig. 8 is a similar view showing the partial application of the intermediate broader stripe or all or of ignition material.

Fig. 9 illustrates a completed match book as 50 provided with the ignition material.

Referring to the drawings, 10 designates a portion of an endless flexible carrier composed of hingedly connected link members in which match 55 cards M and covers C with the folded ends c

of the covers projecting beyond the carrier, are assembled and bound together in book-form; thence transported to and past mechanism whereby ignition material of the consistency of paint is applied exteriorly to the under surfaces 5 of the projecting cover folds, and thence carried through an extended drying path.

The means for actuating the carrier 10 includes a gear 11 which meshes with the rack teeth 12 of the carrier chain in the region of the paint-applying station. This gear is fast on the forward end of a transverse shaft 13 having its bearing in a support 14 on the "painter" stand 15. Fast on the rearward end of the shaft 13 is a gear 16 in mesh with a pinion 17 on a shaft 18 which is suitably connected with and driven from a shaft of the match machine, as usual.

The paint-applying mechanism herein illustrated as an embodiment of my invention comprises a peripherally grooved wheel 19 and a 20 peripherally knurled wheel 20, the former in advance of the latter and the two wheels being mounted directly under and in close relation to the path of the projecting folded ends of the covers. The peripheral spaced ribs or flanges 21 25 of the wheel 19 are arranged and adapted to apply to the underside of each of the projecting end folds two narrow parallel stripes of ignition paint which define the longitudinal edges of the ignition surface. The knurled periphery of the 30 wheel 20 is arranged and adapted to apply to the end fold of the cover a broader stripe of ignition material which efficiently covers the uncoated space between and merges with the two narrow stripes of paint previously applied by the 35 wheel 19, thus ensuring a rectangular ignition or striking surface having uniform parallel longitudinal edges. In Fig. 7 is represented a portion of a match book having on its cover fold the two parallel narrow stripes, 22, of ignition material, 40 and in Fig. 8 such cover is shown with the intermediate broader stripe 23 partially applied thereto.

As illustrated the paint applying wheels 19 and 45 20 are fast on the rearward ends of parallel transverse shafts 24 and 25, respectively, which have their bearings 26 in a frame 27 on the "painter" stand 15. This frame supports the usual guide trough 28 for the upper run of the travelling carrier rearwardly of and adjacent 50 such wheels. The shafts 24 and 25 are concurrently driven clockwise by means of suitable gearing including gears 29 fast on the rearward ends of the respective shafts 24 and 25. The gears 29 mesh with and are driven at the same speed 55

and in the same direction by a gear 30 fast on a lower transverse shaft 31 which has its bearings in the frame 27. The shaft 31 has fast on its forward end the usual paint transfer wheel 32 which is mounted to rotate with its lower portion immersed in the paint container 33 on the stand 15, and with the upper peripheral portion of the wheel in contact or nearly so with the peripheries of the respective wheels 19 and 20. Fast on the rearward end of the shaft 31 is a gear 34 which meshes with and is driven by the gear 16 hereinbefore referred to.

The ratio of the gearing just described is such that during the longitudinal travel of the upper run of the carrier 10 the paint applying wheels 19 and 20 are concurrently driven in timed relation to the carrier, and that the rotating paint transfer wheel 32 progressively carries up a quantity of the ignition material from the container 33 to the opposing peripheral surfaces of the respective wheels 19 and 20, which latter wheels, in turn, successively apply the narrow stripes and the intermediate stripe of material to the opposed folds of the covers of the travelling books borne by the carrier, as previously mentioned.

Mounted on the cap of the bearing 26 for the shaft 25 is a scraper blade 36 which is arranged in co-operative relation with the periphery of the wheel 20 to regulate the amount of ignition material carried up to the cover by such wheel, and mounted on the trough 28 in similar relation to the wheel 19 is another scraper 37 which regulates the amount of the material carried to the cover by the latter wheel. Also mounted on the trough, adjacent the respective paint applying wheels, are two upstanding brackets 38 having bifurcated portions in the legs 39 of which are supported eccentric pins 40. One of the bearings of each of the bifurcated portions is split, as at 41, to constitute a clamp, and is provided with a screw 42 by proper manipulation of which the pin can be clamped or released. Upon each of the eccentric pins 40 is loosely fitted the perforated rearward end of a forwardly extending arm 43, the opposite end of which arm has loose thereon a flanged hold-down wheel which is preferably provided with ball bearings 44. The body 45 of this wheel overhangs the adjacent grooved paint applying wheel 19 and rolls upon the interposed folded portions of the book covers, while the extended flange 46 of the wheel serves as an end stop for the adjacent travelling covers. The hold-down wheel is resiliently urged down by means of a retracting spring 47 which is secured to the adjacent bearing 26 and to an angle bracket 48 which is fastened on the arm 43. Fitted in each arm, adjacent its pin 40, is a vertical set-screw 49 which is arranged to overlie and bear against a suitably-disposed lug 50 on the bracket 38. Hence by adjusting the screw 49 the arm 43 and therewith the hold-down wheel can be nicely raised and lowered within limits as desired, in order to effect and maintain correct pressure of such wheel on the books to ensure the efficient contact of their stapled folds with the underlying paint applying wheel; it being noted that the spring 47 allows the hold-down wheel to adapt itself to books of varying thicknesses. Also by releasing and properly turning the eccentric pin 40 the arm 43 and its flanged hold-down wheel can be adjusted forward or backward in a manner to ensure the correct setting of the folded end of the book cover in respect to the periphery of the adjacent paint applying wheel 19 or 20, as the case may be. This done

the pin can be secured in its position of adjustment by manipulation of the clamp screw 42.

On the guide trough 28 are mounted two spaced brackets 51 which support a bar 52 that extends longitudinally of and above the carrier and is effective not only to hold the underlying carrier links in contact with the rack gear 11, but also slidably to hold down the books while they are passing over the paint wheels 19 and 20.

It is to be understood that the invention is not limited to the particular exemplifying form thereof herein disclosed, as the mechanisms may be modified within the principle of the invention and the scope of the appended claims.

I claim:

1. The combination with a travelling carrier for a succession of match books having end folded cover portions, of means for applying ignition material to a surface of each folded portion, said means comprising an element constructed and arranged to apply spaced narrow stripes of material to said surface and an element constructed and arranged to apply to said surface an intermediate stripe merging with the narrow stripes, means for supplying ignition material to said elements, and means for actuating said elements in timed relation to the carrier.

2. The combination with a travelling carrier for a succession of match books having end folded cover portions, of means for applying ignition material to a surface of each folded portion, said means comprising a wheel constructed and arranged to apply spaced narrow stripes of material to said surface and a wheel constructed and arranged to apply to said surface an intermediate stripe merging with the narrow stripes, means for supplying ignition material to said wheels, and means for rotating said wheels in the same direction and in timed relation to the carrier.

3. The combination with a travelling carrier for a succession of match books having end folded cover portions, of means for applying ignition material to a surface of each folded portion, said means comprising a wheel having spaced peripheral flanges for applying correspondingly spaced narrow stripes of material to said surface and a wheel having a peripheral portion for applying to such surface an intermediate stripe merging with the narrow stripes, means for supplying ignition material to said wheels, and means for rotating said wheels in the same direction and in timed relation to the carrier.

4. The combination with a travelling carrier for a succession of match books having end folded cover portions, of means for applying ignition material to a surface of each folded portion, said means comprising a wheel having spaced peripheral flanges for applying correspondingly spaced narrow stripes of material to said surface and a wheel having a peripheral portion for applying to such surface an intermediate stripe merging with the narrow stripes, resilient pressure means overhanging said wheels to bear upon the folded cover portion, and means for rotating said wheels in the same direction and in timed relation to the carrier.

5. The combination with a travelling carrier for a succession of match books having end folded cover portions, of means for applying ignition material to a surface of each folded portion, said means comprising a wheel having spaced peripheral flanges for applying correspondingly spaced narrow stripes of material to said surface and a wheel having a peripheral portion for applying to such surface an intermediate stripe.

merging with the narrow stripes, resilient pressure wheels overhanging said paint-applying wheels to bear upon the folded cover portion, and means for rotating the latter wheels in the same direction and in timed relation to the carrier.

5 6. The combination with a travelling carrier for a succession of match books having end folded cover portions, of means for applying ignition material to a surface of each folded portion, said means comprising a wheel having spaced peripheral flanges for applying correspondingly spaced narrow stripes of material to said surface and a wheel having a peripheral portion for applying to such surface an intermediate stripe merging with the narrow stripes, resilient pressure means overhanging said wheels to bear upon the folded cover portion, and means for adjusting said pressure means transversely of the wheels.

10 7. The combination with a travelling carrier for a succession of match books having end folded cover portions, of means for applying ignition material to a surface of each folded portion, said means comprising a wheel having spaced peripheral flanges for applying correspondingly spaced narrow stripes of material to said surface and a wheel having a peripheral portion for applying to such surface an intermediate stripe merging with the narrow stripes, resilient pressure means overhanging said wheels to bear upon the folded cover portion, and means for adjusting the force of said pressure means transversely of the wheels.

15 8. The combination with a travelling carrier for a succession of match books having end folded cover portions, of means for applying ignition

material to a surface of each folded portion, said means comprising a wheel having spaced peripheral flanges for applying correspondingly spaced narrow stripes of material to said surface and a wheel having a peripheral portion for applying to such surface an intermediate stripe merging with the narrow stripes, resilient pressure means overhanging said wheels to bear upon the folded cover portion, means for adjusting the force of said pressure means, and means for adjusting 10 said pressure means transversely of the said wheels.

9. The combination with a travelling carrier for a succession of match books having end folded cover portions, of means, including a wheel, 15 for applying ignition paint to a surface of each folded portion, a hold-down wheel overhanging said paint-applying wheel and having a peripheral flange constituting an end stop for the books, and means for resiliently supporting said hold- 20 down wheel in the path of the folded portions of the books.

10. The combination with a travelling carrier for a succession of match books having end folded cover portions, of means, including a wheel, 25 for applying ignition paint to a surface of each folded portion, a hold-down wheel overhanging said paint-applying wheel and having a peripheral flange constituting an end stop for the books, means for resiliently supporting said hold-down 30 wheel in the path of the folded portions of the books, and means for adjusting said hold-down means transversely of the paint-applying wheel.
